US00D705364S

(12) **United States Design Patent**
Miller et al.

(10) **Patent No.:** US D705,364 S
(45) **Date of Patent:** ** *May 20, 2014

(54) **OVAL HOLE CARD READER**

(75) Inventors: **Arthur C. Miller**, Las Vegas, NV (US);
Dean A. Isaacs, Las Vegas, NV (US)

(73) Assignee: **Tech Art, Inc.**, Las Vegas, NV (US)

(*) Notice: This patent is subject to a terminal disclaimer.

(**) Term: **14 Years**

(21) Appl. No.: **29/401,723**

(22) Filed: **Sep. 14, 2011**

(51) **LOC (10) Cl.** 21-01

(52) **U.S. Cl.**

USPC **D21/396**

(58) **Field of Classification Search**

USPC D21/307-208, 334-368, 376-397;
273/236-287, 288-291; D14/385

See application file for complete search history.

(57) **CLAIM**

The ornamental design for oval hole card reader, as shown and described.

DESCRIPTION

FIG. 1 is a left front perspective view of my new design,
FIG. 2. is a top plan view thereof,
FIG. 3. is a right side elevational view thereof.
FIG. 4. is a front elevational view thereof.
FIG. 5 is a bottom plan view thereof.
FIG. 6 is a rear elevational view thereof,
FIG. 7 is a right side elevational view thereof.
FIG. 8 is a right front perspective View thereof,
FIG. 9 is a left rear perspective view thereof,
FIG. 10 is a right rear perspective view thereof.
FIG. 11 is a left front perspective view of a third embodiment
of the invention.
FIG. 12. is a top plan view thereof.
FIG. 13, is a right side elevational view thereof.
FIG. 14, is a front elevational view thereof,
FIG. 15 is a bottom plan view thereof,
FIG. 16 is a rear elevational view thereof,
FIG. 17 is a right side elevational view thereof,
FIG. 18 is a right front perspective view thereof,
FIG. 19 is a left rear perspective view thereof; and,
FIG. 20 is a right rear perspective view thereof.
The broken line showing of mounting and other elements on
the bottom of the design is included for the purpose of illus-
trating portions of the "article" and forms no part of the
claimed design.

1 Claim, 20 Drawing Sheets
